Primary Examiner—Bernard Ansher
Attorney, Agent, or Firm—Samuel C. Miller, III

[21] Appl. No.: 879,621

[57] CLAIM

[22] Filed: Feb. 21, 1978

The ornamental design for a telephone, substantially as
shown and described.

[51] Int. Cl. ..... D14—03

DESCRIPTION

[52] U.S. Cl. D14/53; D21/156;

FIG. 1 is a perspective view of a telephone showing my
new design;

D14/69

FIG. 2 is a bottom plan view thereof;

[58] Field of Search ..... D34/15 R; D21/156;

FIG. 3 is a side elevational view thereof, the side oppo-
site being a mirror image.

D14/69, 53, 60; 11/157; 179/178, 179, 100 D,

The characteristic feature of my design resides in the
telephone dialing base plate in combination with a
stuffed animal figure.

100 R
